ARMATURE MOUNTING FOR CARBON PILE
VOLTAGE REGULATORSJohn Gartner, Hasbrouck Heights, N. J., assignor
to Bendix Aviation Corporation, Teterboro,
N. J., a corporation of Delaware

Application February 28, 1944, Serial No. 524,236

6 Claims. (Cl. 175—342)

1

The present invention relates to voltage regulators of the carbon pile type, and is concerned primarily with the novel mounting for the armature in the assembly.

A carbon pile voltage regulator ordinarily includes a so-called "magnetic pot," which has assembled therewith a movable armature that is affected by variations in the strength of the magnetic field generated by the magnetic pot to vary the pressure on the carbon pile. Heretofore it has been the practice to mount this armature on a leaf spring assembly which is intended to accommodate and compensate for movement of the armature under the influence of the magnetic field. However, various difficulties have attended this known practice and it is the purpose of the present invention to obviate such difficulties.

Accordingly, an important object in view is the provision of the carbon pile regulator, including an armature that is mounted on a flexible diaphragm. In carrying out this idea, the flexible diaphragm is mounted on the top flange now present in magnetic pots of conventional design, and the armature is carried on the under face of this diaphragm.

In view of the need for supplying a yieldable force which will oppose the magnetic influence of the pot, a further object is the provision, in a carbon pile voltage regulator, of a pot, including a core which carries such yieldable means.

More in detail, an end in view is the provision of a core, including a plunger that engages the armature together with spring means for actuating the plunger. Associated with the spring means is a thermostatic device that is responsive to changes in temperature to vary the effective force of the spring.

In view of the tendency of the armature to vibrate the invention has, as a further object, the provision of means for dampening vibration of the armature. This end is achieved by the mounting of the diaphragm which provides an air chamber therebeneath. The air chamber is sealed by a gasket which may be placed around the top of the core in the magnetic pot. This air chamber functions to yieldably oppose movement of the armature and diaphragm in either direction.

Various other more detailed objects and advantages of the invention such as arise in connection with carrying out the above noted thoughts in a practical embodiment will in part become apparent and in part be hereinafter stated.

The invention, therefore, comprises a mag-

netic pot for a carbon pile voltage regulator, which has mounted thereon a diaphragm carrying an armature. The pot includes a core on which is operatively mounted a plunger, together with a spring and a thermostatic device for varying the effective pressure of said spring.

For a full and more complete understanding of the invention, reference may be had to the following description and accompanying drawing, wherein:

Fig. 1 is a perspective view of the magnetic pot of a voltage regulator on which an armature is mounted in accordance with the precepts of this invention;

Fig. 2 is a section through the mechanism of Fig. 1; and

Fig. 3 is a perspective view developing the various elements in exploded relation.

Referring now to the drawing, wherein like reference characters denote corresponding parts, and first more particularly to Figs. 1 and 2, a magnetic pot, such as ordinarily included in carbon pile voltage regulators, is referred to in its entirety by the reference character P. The pot P comprises a bottom 10 on which upstands a cylindrical wall 11, which in turn carries a top 12 that is surrounded by a lip flange 13. A coil, such as shown at 14 in Fig. 1, is positioned in the pot P and includes lead wires 15 that pass out through a slot 16 formed in the cylindrical wall 11.

The bottom wall 10 is formed with a threaded opening 17 and screwed thereinto is a core 18, the lower threaded extremity of which projects beneath the bottom 10. A nut 19 may be employed to lock the core in the required position.

The top 12 is formed with a central opening 20, which may assume the conical formation illustrated, and into which projects the upper end of the core 18.

A diaphragm 21 has its outer peripheral edge anchored to the flange 13, as by fastening elements shown at 22. The upper face of the diaphragm 21 may carry a carbon pile engaging member 23. The under face of the diaphragm 21 carries a disc-like armature 24, there being an insulating disc 25 interposed between the armature 24 and diaphragm 21. Screws, such as shown at 26, may be employed to secure the armature 24 and insulating disc 25 to the diaphragm 21.

In the showing of Fig. 2, it is evident that the armature 25 is ordinarily maintained in a position slightly spaced above the top 12 and more particularly immediately over the opening 20.

The core 18 is provided with a bore 27 that extends up thereinto from the bottom to the head of the core. This head is formed with an opening 28, as is more clearly shown in Fig. 3. Fitted in the opening 28 is a plunger 29, having a cup shaped head 30. One end of an expansion spring 31 is received in the cup shaped head 30, while the other end of spring 31 abuts the uppermost of a plurality of thermostatic discs 32. It will be noted that the discs 32 are of convex-concave formation, with the discs of each pair arranged in opposite position. The lower portion of the bore 27 is threaded, and screwed thereinto is a screw plug 33 upon which rests the lowermost of the discs 32.

When the mechanism is originally assembled, the core 18 is screwed into the opening 17 a proper distance and locked in this position by the nut 19. The screw plug 33 may then be adjusted to place the spring 31 under a required degree of compression. In this position, the pin 29 will abut the under face of the armature 24.

As the magnetic influence of the core 18 varies in accordance with variations in the voltage of the coil 14, the armature 24 is affected and through the medium of the member 23 the pressure on the carbon pile is correspondingly varied. Should the armature be pulled downwardly, such movement is resisted by the spring 31. Any temperature changes are adequately accommodated by the thermostatic discs 32.

It is evident that if the space defined by the flange 13, diaphragm 21, and top 12 is sealed off an air chamber will be provided beneath the diaphragm 21. Accordingly a gasket 34 is placed about the top of the core 18, and this gasket has lips that enclose the edge of the opening in the top 12. An air-tight seal is thus provided and air chamber 35 is established. This chamber 35 acts as a dampener to resist and inhibit vibrations of the armature 24.

While only one embodiment of the invention is hereinbefore set forth, it is to be clearly understood that the invention is not to be limited to the exact construction illustrated and described, because various modifications of these details may be provided in putting the invention into practice within the purview of the appended claims.

What is claimed is:

1. In a carbon pile regulator, a magnetic pot including a core, a diaphragm having its outer edge anchored to said pot, an armature carried by said diaphragm, said diaphragm arranged in relation to said pot so as to dampen vibration of said armature, a plunger movably mounted on said core and having an upper end engaging said armature, and an expansion spring within said core engaging said plunger.

2. In a carbon pile voltage regulator, a magnetic pot including a core, a diaphragm having its outer edge anchored to said pot, an armature carried by said diaphragm, a plunger movably mounted in said core and having a free end engaging said armature, an expansion spring operatively engaging the other end of said plunger, and a thermostatic device associated with said spring for varying the effective force thereof in accordance with temperature changes.

3. In a carbon pile regulator, a magnetic pot including a core and an upstanding peripheral flange, a diaphragm having its outer edge anchored to said flange, an armature carried by said diaphragm, a gasket about the top of said core and cooperating with said pot, flange and diaphragm to provide an air chamber for yieldably

opposing movement of said diaphragm, and yieldable means within said core engaging said armature for resisting movement thereof toward said core.

4. In a carbon pile regulator for maintaining a predetermined electrical condition, the combination comprising, an electromagnet including a magnetic core, a diaphragm having an annular outer edge, an annular member carried by the electromagnet, means fastening the outer edge of said diaphragm in sealing relation to one end of said annular member so as to seal said one end, an armature fixedly connected to said diaphragm and flexibly supported thereby at one side of said diaphragm, said armature positioned within said annular member and in spaced relation to said member and said magnetic core, a carbon pile regulating element positioned at the opposite side of said diaphragm and in concentric relation to said armature and diaphragm, and said diaphragm including annular corrugations for yieldably permitting axial movement of said armature and element relative to said core.

5. In a carbon pile regulator for maintaining a predetermined electrical condition, the combination comprising, an electromagnet including a magnetic core, a diaphragm having an annular outer edge, an annular member carried by the electromagnet, means fastening the outer edge of said diaphragm in sealing relation to one end of said annular member so as to seal said one end, an armature fixedly connected to said diaphragm and flexibly supported thereby at one side of said diaphragm, said armature positioned within said annular member and in spaced relation to said member and said magnetic core, a carbon pile regulating element positioned at the opposite side of said diaphragm and in concentric relation to said armature and diaphragm, said diaphragm including annular corrugations for yieldably permitting axial movement of said armature and element relative to said core, and spring means opposing movement of said armature and element toward said core.

6. In a carbon pile regulator for maintaining a predetermined electrical condition, the combination comprising, an electromagnet including a magnetic core, a flexible corrugated diaphragm having an outer edge, a member carried by the electromagnet, means fastening said diaphragm in sealing relation to said member at said outer edge, an armature positioned within said member and fixedly connected to one side of said flexible diaphragm, said armature axially movable relative to said core, a carbon pile regulating element positioned at the opposite side of said diaphragm in concentric relation to said armature and diaphragm, said diaphragm flexibly supporting said element and armature in relation to said core, and means yieldably opposing movement of said element and armature toward said core.
